ATTORNEY.

UNITED STATES PATENT OFFICE.

CHARLES L. WILSON, OF LOS ANGELES, CALIFORNIA, ASSIGNOR TO CHARLES LEWIS WILSON, INCORPORATED, A CORPORATION OF CALIFORNIA.

SHOWER AND DRESSING ROOM UNITS.

Application filed December 19, 1924. Serial No. 757,054.

To all whom it may concern:

Be it known that I, CHARLES L. WILSON, a citizen of the United States, residing at Los Angeles, in the county of Los Angeles and State of California, have invented certain new and useful Improvements in Shower and Dressing Room Units, of which the following is a specification.

This invention is a shower room construction affording privacy while dressing and undressing, passing to and from the showers, and using said showers; and is particularly adapted for use by gymnasium classes of females.

More particularly it is the object of the invention to provide individual dressing rooms conveniently accessible to individual shower rooms, by positioning said shower rooms and dressing rooms at opposite sides of a central corridor, and to provide for readily converting said central corridor into a series of private, transverse passageways between opposite shower and dressing rooms, so that said passageways may be utilized as a part of the dressing space and also afford means whereby the members of a class may privately enter and leave their individual shower rooms.

It is a still further object of the invention to close the shower rooms after the members of a class have entered the same, and at the same time to reconvert the corridor into an open passageway extending the length of the series of rooms, to insure all of the members of the class leaving their dressing rooms and entering the showers, and also provide privacy while under the showers.

It is a still further object of the invention to operate the corridor converting means and the closure means for the shower rooms from a central control, and to also regulate the flow from the showers and the temperature of the water from a central control, so that classes having a large membership may be efficiently handled and their movement expedited and maintained upon a predetermined schedule.

It is a still further object of the invention to provide for locking the shower rooms against unauthorized use, while permitting an authorized person such as a janitor, to open and close the respective shower rooms independently of the central control, for

the purpose of entering said rooms when cleaning the same.

Further objects of the invention will be readily understood from the following description of the accompanying drawings, in which:

Fig. 1 is a plan view of the improved construction, partly in horizontal section.

Fig. 2 is a transverse vertical section on the line 2—2 of Fig. 1.

Figs. 3 and 4 are detail vertical sections 65 on the lines 3—3 and 4—4 of Fig. 1.

Fig. 5 is a detail transverse section on the line 5—5 of Fig. 3.

The improved construction may include any number of units and may be arranged 70 with one or more series of said units, the form of the invention illustrated comprising two series of units arranged back to back; and the drawings of said construction being broken away in Fig. 1 to indicate any 75 desired length of said series, in order that any number of units may be provided in a series.

The structure is built into a large room having floor 1, end wall 2, and side walls 3, 80 and includes a central partition 4 extending lengthwise of the room to wall 2, and preferably terminating short of the ceiling of the room. This partition forms the back for the two series of units extending lengthwise of the room at the respective sides thereof.

A transverse partition 5 extends across the end of partition 4 which is remote from end wall 2, and projects beyond opposite faces thereof to the desired depth for individual shower rooms, the top of partition 5 preferably terminating at the top of partition 4 and having a frame 6 connecting said parts to the end wall 2. Partitions 7 preferably 95 terminating short of the top of said frame are mounted therein, and project from partition 4 in spaced relation longitudinally thereof so as to form a series of shower rooms A along each side of the central partition. 100

Partitions 8 connected by a frame 9 and preferably the height of partition 4, project from side walls 3 in transverse alinement with partitions 5 and 7, so as to form a series of private dressing rooms B along the length of the room, said dressing rooms and the shower rooms thereby opening opposite

one another onto central corridors 10 which extend the length of the series of rooms.

Doors 11, preferably the height of partitions 7, are hinged to frame 6 so as to close 5 the shower rooms to the central corridors, and the doors for each series of rooms are hinged to swing in the same direction and away from end wall 2.

The corridors 10 are of such width that 10 when doors 11 are swung open and cross-wise of the corridors, the swinging edges of the doors will abut against partitions 8, thereby dividing the central corridors into a series of private transverse passageways 15 between opposite shower and dressing rooms.

The shower rooms A are provided with usual shower heads 13, connected to a common supply pipe 14 in partition 4, and the 20 floors of the shower rooms are preferably sunk below the level of corridors 10 as shown at 15, to insure proper drainage.

A central control for the showers is positioned exteriorly of the shower rooms, 25 and may be mounted on the outside of partition 5 for convenient access to the attendant in charge of the class using the showers. The central control is shown as a usual mixing valve 16 connected to pipe 14 30 and to hot and cold water pipes 17, and may include a usual thermostatic control (not shown).

The dressing rooms B are preferably provided with raised floors 18 so that they will 35 remain dry, said floors terminating short of the rear of said dressing rooms and the walls 3. The floor 1 of the room in which the shower units are built, is spaced from side walls 3 in rear of flooring 18 as shown 40 at 19, so as to form an air space at the rear of the dressing rooms which communicates through openings 19 with the air space in hollow walls 20 of the portion of the building below floor 1.

Partitions 21 extend across the rear of the dressing rooms at the front of said air space, and the tops of the dressing rooms are preferably closed between said partitions and the walls 3 as shown at 22. Benches 50 23 the width of the dressing rooms, project forwardly from partitions 21 at a suitable height, and the portions of said partitions above said benches form frames for the open fronts of a series of compartments C in the 55 air space in rear of said partitions.

The compartments C are superimposed and preferably arranged in a plurality of vertical series in each dressing room, and are formed by partitions 24 extending from 60 the frame formed by partitions 21 to the side walls 3. The fronts of the compartments are closed by suitable doors 25, and said doors and the partitions 24 have openings therethrough, preferably by forming 65 the same of mesh material, so that air may

freely circulate through hollow walls 20, openings 19, and the respective compartments C into the dressing rooms.

The doors 11 for each series of shower rooms, are dependently swung to either of 70 their operative positions closing the shower rooms or dividing the central corridors 10, the operating mechanism having a central control preferably positioned adjacent the water control 16, so that a single attendant 75 may operate the entire structure.

As an instance of this arrangement a slide rod 27 extends the length of each series 80 of shower rooms, and is preferably mounted in guides 28 projecting upwardly from partitions 7 to a height providing sufficient head room for the users of the showers. Links 29 are pivoted to this slide rod and to the respective doors 11 in spaced relation from the hinged edges of the latter, so that shifting of said rod in opposite directions 85 will swing the doors to their respective operative positions.

The control mechanism for shifting each 90 rod 27 is illustrated as comprising a vertical shaft 30 journaled in bearings 31 on the outside of partition 5, said shaft having a crank arm 32 connected by a link 33 to the rod 27, so that turning of the shaft will shift the slide rod in opposite directions. The end of the slide rod and the link 33 95 which is pivoted at its respective ends to said rod and to the crank arm, may be guided in their movement through a suitable opening 34 in partition 5.

An arm 35 projecting from shaft 30, is provided with a handle 36 for turning the shaft, and a stationary plate 37 below arm 35 is provided with locking recesses 38 adapted to be engaged by a bolt 39 on arm 35, for locking the shaft when doors 105 11 are in either of their operative positions. The bolt 39 is projected or retracted for engagement or disengagement with recesses 38, by a suitable key controlled lock mechanism 110 mounted in the end of arm 35.

In order to pivotally connect the doors 11 to the links 29, the upper hinges for the doors have their straps 41 which are fixed to the faces of said doors, laterally extended 115 and terminating in vertical pins 42 projecting above the doors in laterally spaced relation from their hinged edges, and the links 29 are pivoted on said pins so that the strain 120 incident to swinging of the doors is placed directly upon the hinge mountings.

The opposite ends of links 29 which are pivoted to rods 27, are arranged for adjustment of said links to insure equal swinging 125 of all of the doors. For this purpose arcuate slots 43 are preferably provided at the rear ends of the links, and pins 44 pivotally mounted in rods 27, are fixed in adjusted position along said slots, by nuts 45.

The pivotal connections between links 29 130

and pins 42 are normally locked, so that all of the doors 11 may be locked in closed position by locking the shafts 30, but said pivotal connections between links 29 and pins 42 are adapted for individual release, so that any shower room may be entered by a janitor or the like, without opening the doors of all of the shower rooms through operation of the central control.

10 For this purpose the outer ends of links 29 may be separable hollow structures 46 adapted to telescope in the main portions of said links, with pins 42 journaled in the undersides of said separable end pieces.

15 The end pieces 46 are normally held against sliding disengagement from the main portions of the links, by springs 47 fixed in the latter and having openings in their ends adapted to be received over pins 42 in the hollow end pieces 46.

A usual key controlled lock barrel 47 is mounted in the end of hollow member 46, so that when the proper key D is inserted therein and turned, it will engage the end of spring 47 and lift the same from pin 42, so that end piece 46 may be withdrawn from the main portion of the link 29, and thus permit swinging of the door 11 to which it is pivoted, independently of the central control 30 for the doors of the series.

In operation the parts being in the position shown at the upper portion of Fig. 1, the members of a class enter the respective dressing rooms B through the open central corridors 10, and doors 11 are then swung across the corridors as shown at the lower portion of Fig. 1. Each member of the class is thus provided with a private dressing room and shower room, and communicating 40 corridor space, which latter may be used for dressing purposes in order that the dressing rooms B may be relatively small.

Gymnasium clothes and the like are deposited in compartments C to which the individual members of a class are assigned and provided with keys for the doors 25, so that the circulation of air through said compartments may dry said clothes. The members of the class then enter the shower rooms, the necessity for any clothing being eliminated by the provision of private rooms, and doors 11 are then swung so as to close the shower rooms and reopen the central corridors 10.

55 The showers are regulated by the attendant at the central controls, after which the doors 11 are again swung across corridors 10 so that the dressing rooms may be re-entered through the private passageways; and when the members of the class are dressed, they stand clear of the doors 11, so that the latter may be again swung to closed position against the shower rooms, thereby reopening the central corridors so that the 60 class may leave.

I claim:

1. A room having a plurality of longitudinally spaced transverse partitions at opposite sides thereof forming a central corridor extending the length of said room and compartments one beyond another at opposite sides of said corridor and opening into the latter opposite one another, showers in the respective compartments at one side of said corridor, the compartments at the opposite side of said corridor forming dressing rooms, closure means hinged at the openings for the respective shower rooms and adapted when swung in opposite directions to either close the shower rooms and provide an unobstructed central corridor communicating with the respective dressing rooms or extend across said central corridor and against the openings for the respective dressing rooms so that next adjacent closure means provide 70 side closures for transverse passageways connecting opposite shower and dressing rooms, and means for dependently swinging said closure means to their respective positions.

2. The combination of a corridor, a series 90 of rooms at each side of said corridor opening into the same opposite one another, doors adapted to close the respective rooms at one side of said corridor and provide a nonobstructed corridor communicating with the respective rooms at the opposite side thereof or be swung across said corridor so as to shut off the respective portions of the same between opposite rooms of the respective series, and means for dependently swinging 100 said doors.

3. The combination of a corridor, partitions at the respective sides of said corridor forming a series of shower rooms and a series 105 of dressing rooms opening into the corridor from the respective sides thereof with the respective shower and dressing rooms opposite one another, hinged doors for said shower rooms adapted to close the latter to said corridor and provide a nonobstructed corridor communicating with the respective dressing rooms or be swung across said corridor for abutment against the partitions forming the dressing rooms so as to shut off the respective portions of the corridor between opposite shower and dressing rooms.

4. The combination of a corridor, a series 110 of rooms at each side of said corridor opening into the same opposite one another, doors adapted to close the respective rooms at one side of said corridor or be swung across said corridor and provide a nonobstructed corridor communicating with the respective rooms at the opposite side thereof so as to shut off the respective portions thereof between opposite rooms of the respective series, operating means for dependently swinging said doors, and means for releasing the respective doors from said operating means 120 for independent swinging thereof.

5. The combination of a corridor, a series of shower rooms at one side of said corridor, a series of dressing rooms at the opposite side of the corridor, said shower and dressing rooms opening into said corridor opposite one another, doors adapted to close the shower rooms to said corridor and provide a nonobstructed corridor communicating with the respective dressing rooms or be swung across said corridor for shutting off the respective portions thereof between opposite shower and dressing rooms, showers in the respective shower rooms, and means for dependently controlling said showers.
- 15 6. A dressing room having an opening through its floor at the rear thereof, vertically spaced horizontal partitions at the rear wall of said dressing room above said opening, said partitions forming superimposed compartments, and having openings therethrough for circulation of air through said floor opening and said compartments, and doors having openings therethrough closing the fronts of the respective compartments to said dressing room.
7. The combination of a corridor, a series of rooms at each side of said corridor opening into the same opposite one another, hinged doors adapted to close the respective rooms at one side of said corridor and provide a nonobstructed corridor communicating with the respective rooms at the opposite side thereof or be swung across said corridor so as to shut off the respective portions thereof between opposite rooms of the respective series, the hinges of said doors having lateral extensions terminating in vertical pins projecting above said doors in spaced relation from their hinged edges, links pivoted at one end on said pins, and an operating slide having the opposite ends of said links pivoted thereto so that shifting of said slide will dependently swing said doors.
- 35 8. The combination of a corridor, rooms at the respective sides of said corridor opening into the latter opposite one another, and means for closing the rooms at one side of said corridor and provide a nonobstructed corridor communicating with the respective rooms at the opposite side thereof or transversely shutting off the portions of the corridor between the rooms at opposite sides thereof.
9. The combination of a corridor, a series of rooms at each side of said corridor opening into the same opposite one another, doors adapted to close the respective rooms at one side of said corridor and provide a nonobstructed corridor communicating with the respective rooms at the opposite side thereof or be swung across said corridor so as to shut off the respective portions thereof between opposite rooms of the respective series, pins on the respective doors, links having ends slidable longitudinally of said links journaled on said pins, means for releasably locking the respective slidable ends to their links, and means for dependently shifting said links so as to dependently swing said doors.
- 15 10. The combination of a corridor, a series of rooms at each side of said corridor opening into said corridor opposite one another, doors adapted to close the respective rooms at one side of the corridor and provide a nonobstructed corridor communicating with the respective rooms at the opposite side thereof or be swung across said corridor so as to shut off the respective portions thereof between opposite rooms of the respective series, links pivoted at one end to the respective doors, an operating slide having the opposite ends of said links pivoted thereto so that shifting of said slide will dependently swing said doors, and means for adjusting the respective links to cause equal swing of said doors.
- 20 11. The combination of a corridor, a series of rooms at each side of said corridor opening into the latter opposite one another, doors adapted to close the respective rooms at one side of said corridor and provide a nonobstructed corridor communicating with the respective rooms at the opposite side thereof or be swung across said corridor so as to shut off the respective portions thereof between opposite rooms of the respective series, an operating slide, links pivoted to the respective doors and said slide so that shifting of the latter will dependently swing said doors, and means for releasably locking said slide when shifted so as to swing said doors to either of their operative positions.
- 25 In testimony whereof I have affixed my signature to this specification.
- 30 CHARLES L. WILSON.
